United States Patent

Des. 240,145
Patented June 1, 1976

240,145

MAGNETIC MIXING BAR

Leonard E. Brown and Larry E. Brown, Morton Grove, Ill., assignors to Parkside Industries, Chicago, Ill.

Filed Feb. 24, 1975, Ser. No. 552,383

Term of patent 14 years

Int. Cl. D24—99

U.S. Cl. D32—2 C

FIG. 1

FIG. 2

FIG. 3

FIG. 1 is a top plan view of a magnetic mixing bar showing the new design;

FIG. 2 is a front elevation thereof; and

FIG. 3 is a perspective view thereof.

The undisclosed bottom and side portions are identical to the views shown respectively in FIGS. 1 and 2.

We claim:

The ornamental design for a magnetic mixing bar, substantially as shown and described.
